SHUTTLE CHECK FOR LOOMS

Clifford Darwin, Worcester, Mass., assignor to
 Crompton & Knowles Loom Works, Worcester,
 Mass., a corporation of Massachusetts

Application April 16, 1945, Serial No. 588,529

3 Claims. (Cl. 139—185)

1

This invention relates to shuttle checking mechanisms for looms and it is the general object of the invention to provide such a mechanism including a floating shuttle binder so constructed that it can be easily manipulated by the weaver.

Shuttle boxes are generally provided with some form of shuttle checking mechanism which is frequently made as a binder mounted so that it can move toward and from the path traversed by the shuttle. The binder is ordinarily in the shuttle path and offers resistance to the shuttle as the latter enters the shuttle box. Shuttle binders of the floating type are so mounted that each end can move toward and from the shuttle path, but such binders are not ordinarily made in such a way that they can be readily moved away from the shuttle path to relieve pressure on the shuttle. It is an important object of my present invention to provide an improved form of binder having a handle made as a part thereof to facilitate binder movement when the shuttle is to be moved out of the shuttle box manually.

It is customary to apply spring pressure to the inner and outer ends of floating binders, these pressures being of different degrees so that the inner end which cooperates with the protector mechanism will move outwardly away from the shuttle path as soon as the shuttle enters the box. As the shuttle continues to travel into the box the outer end of the binder is moved away from the shuttle path. It is another object of my present invention to provide the binder with a handle extending along the binder for such a distance that either the inner or the outer end of the binder can be moved away from the shuttle path depending upon the point at which the withdrawing force is applied to the handle.

In looms operating with two or more shuttles it is customary to provide a gang of shuttle boxes which are stacked one over the other in close vertical relationship. Because of this relationship it has been difficult in the past to manipulate the binders manually, and it is another object of my invention to provide the binder with a handle of less vertical dimension than that of the binder so that each binder will have a hand hold readily accessible without undue interference on the part of an adjacent binder.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a plan view of a shuttle box of the mul-

2

ticell type having binders made according to my present invention,

Fig. 2 is a front elevation of the shuttle box shown in Fig. 1,

Figs. 3 and 4 are diagrammatic views showing the manner in which the inner and outer ends respectively of the binder may be moved depending upon the point at which force is applied to the binder handle,

Fig. 5 is a vertical enlarged section on line 5—5 of Fig. 1,

Fig. 6 is a detailed enlarged section on line 6—6, Fig. 1, but with the shuttle box parts omitted, and

Fig. 7 is a detail vertical section on line 7—7, Fig. 1.

Referring particularly to Figs. 1 and 2, I have shown a lay L having a lay end 10 in which a gang G of shuttle boxes is guided for vertical motion. The inner end of the gang has a tongue 11 received by a lay carried guide 12, and the outer end of the gang may be provided with a similar tongue 13 fitting into a guide 14. As shown in Fig. 2 the lower end of the gang G is connected to a box lifter rod 15 which is moved vertically by box shifting mechanism not shown. A protector finger 16 of the usual type is provided adjacent the inner end of the gang G and normally exerts a rearward force toward the lay end 10.

Each of the upper and lower shuttle boxes 18 and 19 is provided with a binder, these binders being indicated at 20 and 21, respectively, in Fig. 2. Each binder is made preferably of wood and has a leather friction surface 22 and an inner end 23 formed for cooperation with the protector finger 16. The outer end of each binder is formed with a pocket 24 the rear or inner end of which may be provided with a shock absorbing pad 25 made for instance of leather.

A bracket 30 is secured as at 31 to the gang G and has a forward extension 32 which is more or less parallel to the length of the gang G. This extension is provided with upper and lower adjusting screws 33 and 34, respectively, which as indicated in Fig. 1 are provided at their rear ends with spring bearings 35. Check nuts 36 serve to hold each of the screws 33 and 34 in adjusted position. Each binder has associated therewith a compression spring 40 the rear end of which enters the corresponding pocket 24 and the forward end of which is held by the associated bearing 35. The outer or left end of each binder as viewed in Fig. 1 is therefore moved rearwardly

toward the lay end 10 by its compression spring 40.

Rearward movement of the left end of each binder as viewed in Fig. 1 is limited by an adjustable stop. As shown in Fig. 7 there are two of these stops 45 and 46 one for each of the binders, and each stop has a slot 47 to receive a holding bolt 48 which passes through and is held fast with respect to the angle support 30. Each stop is adjustable independently of the other stop and has the adjacent end of the corresponding binder held against it by the associated spring 40. The inner end of the shuttle boxes carries an angle iron stop 49 which cooperates with stops 45 and 46 to limit endwise movement of the floating binders.

In order that each binder may be moved forwardly in order to relieve pressure on the corresponding shuttle the front edge of each binder is cut as indicated in Fig. 5 to provide an elongated handle or knob 50. This handle is of less vertical dimension than the binder to provide ample room between the handles of adjacent binders for the operator's fingers. Behind each handle are top and bottom recesses 51 and 52 for the operator's fingers.

Figs. 3 and 4 indicate diagrammatically the manner in which either the inner or the outer end of a binder can be moved. In Fig. 3 arrow and spring 'a' represent the resilient rearward force exerted on the binder by the spring 40, while the arrow and spring 'b' represent the resilient rearward force exerted by the protector finger 16. Arrow 'c' indicates the point at which the weaver will grasp the handle 50 if he wishes to move the inner or right end of the binder forwardly to the dotted line position shown in Fig. 3. In the relationship indicated in Fig. 3 the leverage and yielding forces represented by 'a' and 'b' will result in movement of the binder to the position in dotted lines. In this position the protector finger has moved forwardly while the outer end of the binder and spring 40 have remained normal.

In Fig. 4 the force for moving the binder forwardly has been moved to the left and is applied at a point adjacent to spring 40, as indicated by arrow 'd'. In this case the binder will move to the dotted line position of Fig. 4 with its outer end advanced, and with the protector finger in normal position. It will be seen that the handle is sufficiently long to permit the weaver to pull it forwardly by applying a force on it either near the center of the binder or near the spring 40 depending upon whether it is desired to move the inner end of the binder or the outer end thereof forwardly.

From the foregoing it will be seen that I have provided a simple form of shuttle binder made with a handle to facilitate its forward movement. It will also be seen that the handle has a vertical dimension less than that of the associated binder so that when the binders are used in a gang of shuttle boxes each binder can be moved forwardly readily without interference on the part of adjacent binders. Also, it will be seen that the handle is of sufficient length so that either the inner or the outer end of the binder can be moved forwardly. It is to be understood of course that after the binder assumes either of the dotted line positions shown in Fig. 3 or 4 a further forward application of force to the handle will move the binder as a whole to a forward position. Fur-

thermore, it will be seen that each binder has its own adjustable stop limiting rearward movement thereof under action of the associated spring 40. The handle is preferably made of wood although this is not an essential feature of the invention.

Having thus described my invention it will be seen that changes and modifications may be made therein by those skilled in the art without departing from the spirit and scope of the invention and I do not wish to be limited to the details herein disclosed, but what I claim is:

1. In a shuttle box for a loom having a protector finger, a binder extending along said box and having one end thereof in engagement with the protector finger, a spring mounted on said shuttle box and engaging the other end of the binder, said protector finger and spring normally holding the binder in the shuttle box for engagement with a shuttle, said spring exerting a greater force on the binder than said protector finger, and a handle integral with the binder and extending along the latter between the protector finger and spring and being of such length that when a force is applied to the end thereof adjacent to said spring the latter will be overpowered while the protector finger remains normal, and when a force is applied to the end of the handle nearer the protector finger the latter will be overpowered while said spring remains normal.

2. In a shuttle box for a loom having a protector finger, a floating shuttle binder, said protector finger engaging one end of the binder and urging said end rearwardly into the shuttle box, a spring mounted on the shuttle box and engaging the other end of the binder and urging the latter rearwardly into the shuttle box, and a handle formed integral with said binder and located on the front part of the latter and extending from a point adjacent to said spring along said binder toward said protector finger.

3. A loom shuttle binder for a shuttle box having a protector finger at one end thereof movable transversely of the shuttle box and having spring mechanism exerting a force transversely of the shuttle box and a transverse binder guide at the other end thereof, said binder including an elongated body of wood and having one end thereof formed for engagement with the protector finger for movement thereby and having the other end thereof formed to slide along said guide and having means to cooperate with said spring mechanism for movement by the transverse force exerted by said mechanism, and a handle formed integrally with said wood body extending therealong between said one end of the binder and said means at said other end of the binder.

CLIFFORD DARWIN.
